SEAL FOR COMBUSTION ENGINES

Samuel R. Puffer, Saugus, Mass., assignor to
General Electric Company, a corporation of
New York

Application April 3, 1935, Serial No. 14,433

1 Claim. (Cl. 286—27)

The present invention relates to combustion engines, more specifically to the arrangement of valve means for controlling the flow of exhaust or combustion gases from a combustion chamber or cylinder to an exhaust conduit or manifold. The usual arrangement includes a valve casing, a valve with a stem slidably disposed in a channel of the valve casing and a disk secured to the stem and in cooperative relation with an opening of the cylinder. The valve is operated by means including a rocker arm disposed in a rocker arm box.

In general practice the exhaust gases, after leaving this valve, are discharged directly to atmosphere or into a conduit or exhaust manifold. The pressure in which is substantially equal to that of the surrounding atmosphere. At times, however, it becomes desirable to utilize available energy in these exhaust gases in a turbine wheel, a waste heat boiler, or by other means. The most efficient utilization of this energy requires that the pressure in the exhaust manifold be appreciably higher than that of the surrounding atmosphere. Under such conditions of increased back pressure it has been observed that the exhaust valves become overheated, the valve stems become pitted and scored and the life of the entire valve structure and other parts cooperating therewith is materially shortened. The principal cause of this difficulty is that with the constant back pressure in the exhaust manifold higher than the surrounding atmospheric pressure, hot exhaust gases flow through the clearance space between the valve stem and the surrounding channel into the rocker arm box. This flow of gases overheats the valve stem, prevents lubricant from entering the space between the valve stem and the channel, and further tends to build up a pressure inside the rocker arm box which causes expelling of lubricant from this box through any opening, however minute.

The object of my invention is to provide an improved construction and arrangement of the type of combustion engines above specified to reduce the injurious effects of exhausting into a manifold or other chamber wherein a relatively high pressure exists.

For a consideration of what I believe to be novel and my invention, attention is directed to the following description and the claim appended thereto in connection with the accompanying drawing.

In the drawing, Fig. 1 is a somewhat diagrammatic view of an internal combustion engine embodying my invention; Fig. 2 is an enlarged detail view of a part of Fig. 1, and Figs. 3 and 4 are modifications according to my invention.

The arrangement shown by way of example in the drawing comprises a combustion engine having a casing 10 to which is flanged a casing 11 of a supercharger. The supercharger in this particular instance has two stages, a first stage 12 with an inlet or suction conduit 13 and an outlet or a discharge conduit 14. The latter forms an air duct to an inlet 15 of a second stage. Interposed in the air duct is a carburetor 16 in which fuel is mixed with the air discharged from the first stage and forced into the inlet 15 of the second stage. The second stage has an outlet 17 which forms an intake for an engine cylinder 18. The engine cylinder 18 is connected to an exhaust conduit or manifold 19 in which the pressure is maintained higher than that of the surrounding atmosphere. The flow of combustion gases from the engine cylinder 18 to the exhaust conduit 19 is controlled by means including a valve mechanism 20. The mechanism, as shown in Fig. 2, comprises a valve stem 21 slidably disposed in a sleeve 22 formed in a valve casing 23. The valve casing 23 in the present instance is integrally united with a portion of the cylinder 18. The lower end of the valve stem is secured to a valve disk 24, which latter is in cooperative relation with a seat 25 on the cylinder 18. The upper end of the valve stem 21 is engaged by a rocker arm 26 held on a fulcrum 27 and connected to a push rod 28. The valve is normally biased towards closing position and held in contact with the right-hand end of the rocker arm 26 by means of a coiled spring 29 surrounding the upper end of the valve stem 21. The latter and the rocker arm 26 are enclosed by a rocker arm box or casing 30. The push rod is enclosed by a tube 30a. The fulcrum 27 and other movable parts of the valve mechanism are lubricated to reduce friction and wear thereof.

During operation the push rod 28 is periodically reciprocated to cause opening and closing of the valve. When the valve is opened or unseated, gases are discharged from the cylinder 18 into the exhaust conduit 19, in which as described above there may be a pressure higher than the surrounding atmospheric pressure. Due to this difference in pressure, the hot exhaust gases normally have a tendency to flow upward into the small clearance existing between the valve stem 21 and the wall of the surrounding channel 22. This flow of hot gases forces out and burns away all lubricant in the clearance space, causes overheating of the valve stem, and by creating a pressure above atmosphere in the rocker arm box, expels the lubricant therefrom. This upward

flow of hot combustion gases with its injurious effects is reduced or eliminated in accordance with my invention by the provision of auxiliary means which cause an artificial draft or blast along the valve stem 21. Preferably I provide means for causing a counter-flow of fluid such as air with respect to the flow of combustion gases. In the present instance I have shown two spaced-apart recesses 31 and 32 formed in the channel 22 and surrounding the valve stem 21 near its lower end. The recess 31 which is formed nearest the valve disk 24 is connected to a conduit 33 for conducting air (or other fluid) under pressure to the recess. The other end of the conduit 33 is connected to a source of air or other fluid having an absolute pressure higher than the (maximum, average) absolute pressure within the exhaust manifold or chamber 19. In this particular instance it is shown connected to the air duct or outlet conduit 14 (Fig. 1) of the first supercharger stage, the connection being made ahead of the carburetor 16 whereby air from the first stage of the supercharger is forced through the conduit 33 into the recess 31 surrounding the valve stem 21. The portion of the channel 22 in the valve casing intermediate the recess 31 and the lower end of the channel is made slightly wider to form a clearance 34 of a width sufficient to permit a flow of air at high velocity from the recess 31 towards the disk or lower portion of the valve stem. This counterflow of air prevents or reduces the flow of combustion gases in the opposite direction. Since the pressure established in the recess 31 is higher than that within the rocker arm box, this higher pressure might cause a flow of air through the clearance space between the valve stem and the channel into the rocker arm box, thereby effecting ejecting of lubricant from this box. To prevent this I provide intermediate the first recess 31 and the rocker arm box a second recess 32 which is vented to atmosphere through a conduit 36. The channel portion 35 intermediate the two recess 31 and 32 has a good sliding or packing fit with the valve stem. The cross sectional area of the conduit 36 and the recess 32 is appreciably larger than that of the clearance between the valve stem and the channel so that any fluid or gases passing through the channel portion 35 will escape to atmosphere without creating in the recess 32 a pressure above atmosphere.

The modification of Fig. 3 comprises a valve casing 40 forming a channel 41 for a valve stem 42. A recess 43 corresponding to the recess 31 of Fig. 2 is formed in the channel 41 and connected to a source 44 of high air or fluid pressure. In accordance with my invention a lower portion 45 of the channel 41 intermediate the recess 43 and the end of the channel 41 is Venturi-shaped and made wide enough to permit the flow of compressed air from the recess 43 towards the lower portion of the stem 42. The arrangement is such that the air is discharged from the recess 43 at high velocity, the velocity being gradually converted into pressure as the air leaves the lower end of the flared or Venturi-shaped channel portion 45, thereby preventing or reducing the flow of combustion gases along the stem in the opposite direction.

The modification of my invention shown in Fig. 4 comprises a valve casing 50 having a channel 51 for accommodating a valve stem 52. Two spaced apart annular recesses 53 and 54 surrounding the valve stem 52 are formed in the channel 51. The recess 53 in this arrangement is connected by a conduit 55 to a space subject to pressure equal to or less than that of the atmosphere, for instance the intake chamber of a compressor. The recess 53 is disposed near the lower end of the valve stem, that is, adjacent the valve disk, whereas the recess 54 is disposed on the side of the recess 53 remote from the valve disk. The recess 54 communicates by a conduit 56 with the atmosphere. The provision of the recess 56 vented to atmosphere is important whenever the other recess 53 is connected to a point of subatmospheric pressure because in this case the existence of low pressure in the recess 53 would cause the lubricant in the upper end of the valve stem and the rocker arm, not indicated, to flow downward along the valve stem. This downward flow of the lubricant is reduced by the provision of means creating a pressure equal to the atmosphere at a point above the recess 53, in the present instance within the recess 54. During operation, exhaust gases are permitted to flow upward along the lower end of the valve stem 52 until they reach the recess 53, whence they are discharged through the conduit 55. Thus, whereas in the arrangement of Figs. 1 and 2 means are provided for creating an artificial flow in downward direction, that is, towards the valve stem, in the arrangement of Fig. 4 means are provided for creating an artificial flow upward along the valve stem, and other means are provided for reducing the flow of air and lubricant from the upper part of the valve stem into the recess 53. Furthermore, whereas in the arrangement of Fig. 2 the lower end portion 34 of the channel is somewhat wider to define an annular space with the valve stem, in the arrangement of Fig. 4 the lower end of the channel 51 has a sliding fit with the valve stem, similar to the sliding fit intermediate the two recesses 53 and 54 and corresponding to the sliding fit intermediate the recesses 31 and 32 of Fig. 2.

Having described the method of operation of my invention, together with the apparatus which I now consider to represent the best embodiment thereof, I desire to have it understood that the apparatus shown is only illustrative and that the invention may be carried out by other means.

What I claim as new and desire to secure by Letters Patent in the United States is:

A stuffing box for an exhaust valve having a stem and a disk for controlling the flow of exhaust gases from a source to an exhaust, means having spaced upper and lower annular recesses surrounding the end of said stem near the disk, means for maintaining in the lower recess a pressure greater than that existing in such exhaust, and means for venting the upper recess to atmosphere, the channel between the lower recess and the disk forming a clearance to permit air contained in the lower recess to flow at high velocity along the stem towards the disk.

SAMUEL R. PUFFER.
